UNITED STATES PATENT OFFICE.

VANCE P. WILKINS, OF LAPORTE, INDIANA, ASSIGNOR OF ONE-HALF TO
EMMET SCOTT, OF LAPORTE, INDIANA.

GAS-METER.

No. 834,854.

Specification of Letters Patent.

Patented Oct. 30, 1906.

Application filed June 26, 1905. Serial No. 266,955.

To all whom it may concern:

Be it known that I, VANCE P. WILKINS, a citizen of the United States, residing in La-
porte, in the county of Laporte and State of
5 Indiana, have invented a new and useful Im-
provement in Gas-Meters, of which the fol-
lowing is a specification.

This invention relates to that class of gas-
meters wherein the interior partitions and
10 gas-passages are formed of sheet-metal sec-
tions or parts bent into the desired shapes
and soldered or otherwise secured together;
and its object has been to increase the capac-
ity of the meter without enlarging its meas-
15 uring devices. My tests with meters em-
bodying the invention have demonstrated
that they have a capacity varying from fif-
teen to twenty-five per cent. over meters of
the same size constructed in the old way,
20 and this increased capacity is obtained by
changing the construction only slightly and
without increasing the cost of manufacture
materially.

The nature of my improvement will be
25 fully understood from the description given
below and from the accompanying drawings,
forming a part of my specification, and in
which—

Figure 1 is a horizontal section, and Fig. 2
30 is a vertical section, of my improved meter.
Fig. 3 is a section on the line 3 3 of Fig. 1.

I show in the drawings a well-known and
standard construction of meter, 5 being the
35 outer casing, 6 the measuring-bellows, and
7 the vertical partition between the bellows; 8,
the gas-supply pipe; 9, the gas-discharge pipe
connected to the pipes of the house or build-
ing; 10, the slide-valves regulating the move-
40 ments of the gas to and from the bellows; 11,
the chamber containing said valves; 12, the
floor or horizontal partition supporting the
valves; 13, the rock-shafts or flag-rods ac-
tuuated by the measuring-bellows; 14, the ro-
45 tating shaft driven from the rock-shafts by
suitable connections adapted to transform
the motion; 15, the worm and pinion whereby
shaft 14 actuates the dial-hands, and 16 the
crank and pitman whereby the shaft 14
50 moves the valves. All of these parts are un-
changed in my construction. The gas takes
the usual course through the meters, enter-
ing at pipe 8, thence into the horizontal pas-
sage 17, and emerging from said passage at
the opening 18 into the valve-chamber 11.

From here it moves through the valves by 55
passages 19 into the bellows and bellows-
chambers, that from the latter returning
again to the valve-chamber and that from
the bellows issuing by passage 20 into the
60 house-pipe 9.

As heretofore constructed the passages 17
and 20 have joined the pipes 8 and 9 at right
angles to the latter, forcing the gas to make
abrupt right-angle turns. In my improve-
ment, however, I change both the joints 65
from a right angle to an angle inclined in
accordance with the direction of the flow
of the gas, this inclination in the construc-
tion illustrated being upward. In order to
effect this change, I cut out the floor 12 70
above each of the passages 17 and 20, as
shown at 21, and the adjacent wall of each of
the pipes 8 and 9, as shown at 22, and cover
the opening thus made with any suitable
construction of cap adapted to close it, the 75
one illustrated at 23 being provided with de-
pending triangular sides 24, and otherwise
adapted to be soldered to the floor 12 and to
the casing around the opening. In this
manner I change the upper angle of each 80
joint in such manner that it forms less of an
obstruction to the movement of the gas than
in the old construction, and I also enlarge
the passages and the openings from the
supply-pipe and to the house-pipes, and the
result is a marked increase in the capacity of
the meter without any increase in the size of
the measuring devices or changing any other
portions of the gas-passages in any respect
whatever. 90

The invention can be readily applied to
existing meters.

It will be understood that I do not wish to
be limited to any particular construction of
cap 23. 95

I claim—

1. A bellows-meter having vertical inlet
and outlet pipes or tubes, a horizontal pas-
sage connecting the inlet-pipe with the valve-
chamber, and a horizontal passage connect-
ing the bellows with the outlet-pipe, the tops
of both said horizontal passages being cut
away at their junction with the pipes and
the openings thus formed being closed by in-
clined caps. 100

2. The bellows gas-meter having vertical
supply and house pipes 8 and 9 and horizon-
tal inlet and outlet passages 17 and 20 each
105

connected to one of said vertical pipes, said pipes and passages being all formed of sheet metal the tops of the passages 17 and 20 being inclined upward at their junctions with the vertical pipes, and the walls of the latter upon the side receiving said passages being also cut out at the junction to correspond to the upward inclination of the tops of the passages.

10 3. The bellows gas-meter having vertical supply and house pipes 8 and 9 and horizon-

tal inlet and outlet passages 17 and 20 each connected to one of said vertical pipes, the tops of the passages 17 and 20 and the adjacent walls of the pipes being cut out at the junctions and the openings thus formed being closed by inclined caps 23. 15

VANCE P. WILKINS.
